Patented Apr. 9, 1918.

FIG. 1

FIG. 2

FIG. 3

Inventor
Elliott Higgins

By Attorney
C. D. Taskins

UNITED STATES PATENT OFFICE.

ELLIOTT HIGGINS, OF SEATTLE, WASHINGTON.

SHOW-CASE.

1,261,812.

Specification of Letters Patent. Patented Apr. 9, 1918.

Application filed March 22, 1917. Serial No. 156,796.

To all whom it may concern:

Be it known that I, ELLIOTT HIGGINS, citizen of the United States, residing at Seattle, in the county of King and State of Washington, have invented a certain new and useful Improvement in Show-Cases, of which the following is a specification.

My invention relates to improvements in show-cases within which may be displayed objects of merchandise, and the object of my invention is to provide a show-case which shall be adapted to be disposed on ground accessible to the public, as a vacant city lot, and within which may be displayed an automobile, a machine, or other articles for sale, and which shall embody a bottom wall comprising a platform fixed on the ground, upon which bottom wall is removably disposed inclosing walls comprising rigidly united vertical side walls and top wall, together with operative mechanical means for elevating said inclosing walls to a height that will permit the disposal upon and removal from said platform of an object for sale; one or more of said vertical side walls being transparent.

I accomplish this object by devices illustrated in the accompanying drawings wherein—

Figure 1 is a plan view of one form of a structure embodying my invention;

Fig. 2 is a view in front elevation of the same; and

Fig. 3 is an enlarged view of the same in vertical section on broken line 3, 3 of Fig. 1.

Referring to the drawings, throughout which like reference numerals indicate like parts, two foundation timbers 4 and 5 are inlaid on the ground parallel with and spaced from each other, and transversely disposed on said timbers 4 and 5 are sills 6 and 7 and floor beams 8 as shown in Fig. 3.

Laid upon the sills 6 and 7 and floor beams 8 is a plank platform 9 upon which may be disposed for display an automobile, or other article of merchandise.

Removably disposed to cover the platform 9 is an inclosing case comprising a rearward vertical wall 10, a frontward vertical wall 11, vertical end walls 12 and 13 and a top wall or roof 14.

The distance between the end walls 12 and 13 and the distance between the rearward wall 10 and the frontward wall 11 is such as will cause the inner surfaces of the lower portions of said walls to be adjacent to the

surfaces of the side edges and end edges respectively of the plank platform 9 when the inclosing case is disposed to rest its bottom edges on that portion of the surfaces of the top of the sills 6 and 7 which is adjacent to the edges of the platform 9, thereby to prevent a displacement of said inclosing case in sidewise and endwise directions.

Preferably the four vertical walls 10, 11, 12 and 13 embody panes of glass or other transparent sheet material thereby to permit articles disposed in the inclosure on the platform 9 to be seen from the exterior of said inclosure, but if desired some of said vertical walls may be made of sheet metal.

The timbers 4 and 5 project rearwardly from the rearward sill 6 for a suitable distance to provide a foundation for a windlass 15 whose base portion 16 is bolted to the top surface of the rearwardly projecting end portions of said timbers 4 and 5, as shown in Figs. 1 and 3.

Fixed on the top portion of the windlass 15 is the lower end of a metal pipe 17 which extends therefrom vertically upward for a distance, thence in a curve forwardly to terminate at a point directly above the center of the platform 9, and rotatably mounted in bearings rigidly attached to the upper end of said pipe 17 is a pulley 18, as shown more clearly in Fig. 3.

The windlass 15 is provided with a winding drum 19 which is provided with a cable 20 that extends therefrom upwardly through the pipe 17 and out of the upper curved end portion thereof to engage with the pulley 18 and to extend vertically downward from said pulley 18 to terminate in a loop 21 which is attached to a suspension bracket 22 which is rigidly fastened to the apex of the top wall or roof 14 of the inclosing case, as shown more clearly in Fig. 3, whereby in response to the operation of the windlass 15 said inclosing case may be raised and lowered when it is desired to place upon or remove from the platform 9 an automobile or other article of merchandise.

I have shown but one form of mechanical means for raising and lowering the inclosing case, but it is obvious that other forms of devices may be employed for such purpose.

In order that the interior of the inclosing case may be illuminated, at required times, I have provided electric lamps 23 fixed to the underside of the roof 14 to which lamps

23 electric current may be conducted by circuit wires, not shown.

Manifestly, the inclosing case may be constructed in such manner that its vertical walls 10, 11, 12 and 13 and its roof 14 may be adapted to be separable so that they may be disposed compactly to facilitate their transportation from one point to another.

10 A show case embodying my invention, in the manner shown and described, may be utilized by disposing it on ground accessible to the general public, as, for instance, in a vacant city lot adjacent to a busy street, where it may serve to display articles of 15 merchandise which are of general interest to the public, as, for instance, an automobile.

The operation of a show case embodying my invention may be described as follows:

20 The windlass 15 is actuated to raise the inclosing case from the platform 9 to a height that will permit the article to be displayed (as, for instance, an automobile) to be disposed on the platform 9 and thereupon the windlass 15 is again actuated to 25 lower the inclosing case to rest upon the sills 6 and 7, thereby to inclose said automobile which will then be observable through the transparent vertical walls of said inclosing case.

30 If desired, movable parts of the windlass 15 may be locked by any well known means to prevent unauthorized persons from raising the inclosing case to gain access to the automobile.

Obviously, changes may be made in the 35 forms, dimensions and arrangement of parts of my invention without departing from the spirit thereof.

What I claim is:

A show case of the class described, which 40 embodies foundation timbers horizontally disposed parallel with and spaced from each other; a platform rigidly secured to the top surface of said foundation timbers and disposed with one of its side edges at a distance 45 from like ends of said foundation timbers; an inclosing case provided with a transparent wall and removably disposed to cover said platform; a windlass rigidly fastened on said foundation timbers in a 50 position between its said like ends and said platform; a metal pipe fixed on the top portion of said windlass to extend vertically upward therefrom for a distance higher than the top of said inclosing case, thence 55 in a curve to terminate at a point above the central portion of the roof of said inclosing case; a pulley rotatably mounted in bearings rigidly attached to the higher end portion of said metal pipe; and a cable 60 operatively associated with said windlass, said metal pipe, said pulley and said inclosing case, whereby said inclosing case may be raised and lowered.

In witness whereof, I hereunto subscribe 65 my name this 16th day of March A. D., 1917.

ELLIOTT HIGGINS.
